(57) **CLAIM**

The ornamental design for a firearm grip, as shown and described.

DESCRIPTION

FIG. 1 shows a perspective view of a first embodiment of a firearm grip;

FIG. 2 shows a front view thereof;

FIG. 3 shows a rear view thereof;

FIG. 4 shows a right side view thereof;

FIG. 5 shows a left side view thereof;

FIG. 6 shows a top plan view thereof; and

FIG. 7 shows a bottom plan view thereof.

FIG. 8 shows a perspective view of a second embodiment of the firearm grip;

FIG. 9 shows a front view thereof;

FIG. 10 shows a rear view thereof;

FIG. 11 shows a right side view thereof;

FIG. 12 shows a left side view thereof;

FIG. 13 shows a top plan view thereof; and

FIG. 14 shows a bottom plan view thereof.

FIG. 15 shows a perspective view of a third embodiment of the firearm grip;

FIG. 16 shows a front view thereof;

FIG. 17 shows a rear view thereof;

FIG. 18 shows a right side view thereof;

FIG. 19 shows a left side view thereof;

FIG. 20 shows a top plan view thereof; and

FIG. 21 shows a bottom plan view thereof.

FIG. 22 shows a perspective view of a fourth embodiment of the firearm grip;

FIG. 23 shows a front view thereof;

FIG. 24 shows a rear view thereof;

FIG. 25 shows a right side view thereof;

FIG. 26 shows a left side view thereof;

FIG. 27 shows a top plan view thereof; and,

FIG. 28 shows a bottom plan view thereof.

The shade lines in the Figures show contour and not surface ornamentation.

The broken lines shown in the Figures show portions of the Firearm Grip which form no part of the claimed design.
